(57) **CLAIM**

The ornamental design for a medical straw, as shown and described.

DESCRIPTION

FIG. 1 is a perspective view of a medical straw, showing my new design;

FIG. 2 is a front elevational view of a medical straw thereof;

FIG. 3 is a rear elevational view of a medical straw thereof;

FIG. 4 is a left side elevational view of a medical straw thereof;

FIG. 5 is a right side elevational view of a medical straw thereof;

FIG. 6 is a top plan view of a medical straw thereof;

FIG. 7 is a bottom plan view of a medical straw thereof; and,

FIG. 8 is a cross-sectional view of a medical straw thereof. The broken lines show portions of the medical straw that form no part of the claimed design. The medical straw is shown with a symbolic break in its length. The appearance of any portion of the article between the break lines forms no part of the claimed design.
